[57] CLAIM

The ornamental design for a combined cigarette and lighter holder, beverage holder and tray for an automobile dash, as shown and described.

DESCRIPTION

FIG. 1 is a right front perspective view of a combined cigarette and lighter holder, beverage holder and tray for an automobile dash, showing my new design and shown in the closed position;

FIG. 2 is a right front perspective view thereof with the beverage holder popped up;

FIG. 3 is a top view of FIG. 1;

FIG. 4 is a front view of FIG. 1;

FIG. 5 is a right side view of FIG. 1;

FIG. 6 is a bottom view of FIG. 1; and

FIG. 7 is a right front perspective view of FIG. 3 with the cigarette and lighter holder in place and the holder in popped up position.

FIG. 1

FIG. 2

FIG. 3

FIG. 4

FIG. 5

FIG. 6

FIG. 7

UNITED STATES PATENT AND TRADEMARK OFFICE

Certificate

Patent No. D. 296,725

Patented: July 19, 1988

On petition requesting issuance of a certificate for correction of inventorship pursuant to 35 U.S.C. 256, it has been found that the above-identified patent, through error and without any deceptive intent, improperly sets forth the inventorship. Accordingly, it is hereby certified that the correct inventorship of this patent is:

Pierre Charet and Duke-Kraai

Signed and Sealed This 2nd Day of January 1990.
